UNITED STATES PATENT OFFICE.

JAMES E. BEAN, (BY JUDICIAL CHANGE OF NAME NOW EDWARD BEAN PARKHURST,) OF MILWAUKEE, WISCONSIN.

MIXING AND VAPORIZING DEVICE FOR MOTORS.

SPECIFICATION forming part of Letters Patent No. 761,192, dated May 31, 1904.

Application filed October 16, 1901. Serial No. 78,783. (No model.)

To all whom it may concern:

Be it known that I, JAMES E. BEAN, residing at Milwaukee, in the county of Milwaukee and State of Wisconsin, have invented a new and useful Improvement in Mixing and Vaporizing Devices for Motors, of which the following is a description, reference being had to the accompanying drawings, which are a part of this specification.

10 My invention has relation to improvements in mixing and vaporizing devices for motors, more especially, although not necessarily, for gasolene-motors.

The primary object had in view is to provide a simple construction wherein the pump ordinarily used for sucking the gasolene or other vapor-gas liquid from a tank is entirely dispensed with and a simple mechanism employed in lieu thereof, which shall be capable 20 of drawing the liquid from the tank and conducting said liquid to the mixing portion of the device, there to be mixed with and atomized by the inflowing air.

A further object resides in providing a simple construction wherein the supply of gasolene may be readily controlled and set to feed a desired quantity of liquid into the mixing portion of the device.

30 A further object resides in providing means whereby certain of the parts which are liable to stoppage may be readily removed for the purpose of cleaning and after being cleaned readily readjusted to place.

With the above and other incidental objects in view the invention consists of the devices and parts or their equivalents, as hereinafter more fully set forth.

In the accompanying drawings, Figure 1 is a longitudinal sectional view of my improvements. Fig. 2 is a plan view of the parts above the tank. Fig. 3 is an end view of Fig. 2, and Fig. 4 is an enlarged sectional view of the oil-feeding device.

Referring to the drawings, the numeral 4 indicates a tank for containing the gasolene or other vapor-gas-producing liquid. In the top of this tank is an opening 5, in which is seated an interiorly-threaded collar 6. Above the tank is a pipe 7, the outer end of which

is open to the external atmosphere. Depending from the pipe 7 is a nipple 8. The lower end of this nipple has a threaded connection with the interior of a coupling 9, which coupling in turn is exteriorly threaded and is screwed into the threaded collar 6. The coupling 9 is provided with a long tube 10, which extends for a desired distance downwardly in the tank, preferably to near the bottom of said tank. Within the coupling 9 is formed a valve-seat 11, against which an upwardly-opening valve 12 is seated, said valve provided with a depending guide-stem 13.

Extending across the interior of pipe 7 and communicating with the nipple 8 is a tube 14. This tube is provided at diametrically opposite points with openings 15 15. If desired, only one opening 50 may be provided and successful results obtained. Rotatably fitting in the tube 14 is a plug 16, said plug being tubular from its lower end upwardly for a desired distance to form a channel 17. The upper end of this channel is intersected by a transverse opening 18. The plug extends outwardly from the upper surface of the pipe and has secured to its upper end an index-arm 19, which is adapted to work over the face of a segmental plate 20, said plate provided upon its upper face with a graduated scale, as clearly shown in the drawings. The end of the arm 19 is extended beyond the outer edge of the segmental plate and is bent around said outer edge and then upwardly, so that its extremity will contact with the under side of said plate. This contacting extremity of the arm on the under side of the plate works over a series of indented marks 21, as shown by dotted lines in Fig. 2, said marks being graduated to conform to the scale-marks on the upper side of the plate and serve as a rack to hold the arm at adjusted position. Secured to the end of the pipe 7 is a coupling 22. This coupling may be secured in any desirable manner; but I prefer to connect it in the manner shown in the drawings, wherein the end of the pipe 7 is shown as having exteriorly threaded thereon a collar 23, said collar provided at its outer end with a shoulder 24. A connecting band or ring 25 surrounds the

- joint between the pipe and coupling, and one end of this band or ring is provided with a shoulder 26, which engages the shoulder 24 of the collar. The opposite end of said ring 5 or band is provided with female threads which engage male threads on the end of the coupling. This particular form of connection provides a means for ready adjustment in case the fittings are not perfect.
- 10 Within the coupling 22 is a partition 27, the horizontal portion of said partition provided with an opening forming a valve-seat 28. Normally closing this opening is a valve 29, which is provided with an upwardly-extending 15 guide-stem 30, said stem fitted and guided in a tubular extension 31. The guide-stem is surrounded by a coiled spring 32, which is confined between the upper side of the valve and the under side of the tubular extension.
- 20 Connected to the outer end of the coupling 22 is a pipe 33, which connects with and conducts the mixture to the cylinder (not shown) of the engine and which cylinder may be of any of the usual and well-known forms of construction.

In the operation of the invention the plug 16 is turned so that its opening 18 is brought into registration with the openings 15 15 of the tube 14. If the maximum amount of gasoline to which the device is capable of feeding is desired, the plug is turned so that the opening 18 is in full registration with the openings 15, or if it is desired to feed a less quantity of gasoline the plug is turned so that there will be only a partial registration of said openings. The graduated scale on the segmental plate determines the extent the handle 19 is required to be turned in order to provide for the feed of a given amount of gasoline, and 40 when the handle is turned to the proper position it is held stationary in that position until it is desired to change the feed. It is obvious that instead of the openings 18 and 15 extending through both sides of the plug 16 and tube 14, respectively, they may extend 45 through one side thereof only and such openings arranged to register at any point where a suction would be produced therethrough.

When the engine mechanism is started, the 50 suction created by the piston on its reciprocation in one direction will overcome the tension of the spring 32 and raise the valve 29. This suction will also draw in air through the open end of the pipe 7, and the air so drawn in and rushing past the tube 14 will cause the gasoline to be drawn up in the tube 10, the ascending gasoline raising the check-valve 12, and flowing above said valve into the passage 17 of the plug 16, thence through the opening 60 18 of said plug, and out of the openings 15 of the tube 14 and into the pipe 7. The check-valve 12 of course serves to prevent the back-flow of the gasoline. The air and gasoline now commingle in the pipe 7, the air having 65 the effect of atomizing and vaporizing the

gasoline. The mixture now flows into the coupling 22, thence through the valve-opening 28 into pipe 33, and finally through said pipe to the cylinder of the engine.

From the construction above described it 70 will be seen that I provide a simple means for drawing the gasoline from the tank without the necessity of employing a suction-pump, as ordinarily used, and I also provide a most efficient means for mixing gasoline and air 75 and atomizing and vaporizing the gasoline, together with provision for accurately regulating the amount of gasoline drawn from the tank.

The small holes 15 15 and 18 are quite liable to become clogged up with dirt, and thereby impair the working of the device. It is to guard against this that I provide for the removability of the plug 16. In order to remove said plug, all that is necessary to be 80 done is to turn the handle 19 until the extremity thereof which is beneath the plate 20 has passed either end of said plate. The plug can then be readily removed and the passage 17 and the opening 18 thereof cleaned 85 without difficulty. When this plug is thus removed, it is also evident that access may be readily obtained to the holes 15 by means of a wire or other device inserted through the end of the pipe 7 and through said holes 15. 90

The extremity of the handle 19, which bears against the under side of the plate 20, not only forms a means by engagement with the indentations 21 for holding the handle in adjusted position, but said end of the handle 100 also prevents the plug from being removed until the handle is turned sufficiently far in either direction for the extremity thereof to clear either end of the plate 20. I would also call attention to the fact that by providing the 105 coupling 9 at the upper end of the tube 10, said coupling having a threaded connection with the nipple 8, the distance the tube 10 extends into the tank 4 may be readily regulated. I would furthermore call attention to the fact 110 that I prefer to provide in the outer end of the pipe 7 a thin partition 34, the rear edge of said partition almost touching the tube 14 and being in line with the outer opening 15 of said tube. Experience has demonstrated that 115 by the employment of this partition the capacity of the device for drawing the gasoline upwardly into the pipe 7 is greatly augmented.

What I claim as my invention is—

1. In a mixing and vaporizing device, the 120 combination of a tank for containing a liquid capable of being converted into gaseous vapor, a pipe having an opening through which air is adapted to pass and enter the interior of said pipe, a tube extending into the tank and having communication with the pipe, a check-valve for controlling the tube, another tube extending across the pipe and in communication with the first-referred-to tube, and provided with an opening, a rotatable part with- 125

in the tube and removably fitted therein, and having a channel extending from its lower end upwardly for a desired distance, said channel being intersected by a transverse opening, and said rotatable part extending above the pipe in position to permit it to be grasped and withdrawn from its surrounding tube, means for turning the rotatable part so as to bring its intersecting opening into or out of registration with the opening of the surrounding tube, and means for drawing or forcing the gas-producing fluid and the air into and through the pipe.

2. In a mixing and vaporizing device, the combination of a tank for containing a liquid capable of being converted into a gaseous vapor, a pipe having an opening through which air is adapted to pass and enter the interior of said pipe, a tube extending into the tank and having communication with the pipe, a check-valve for controlling said tube, another tube extending across the pipe and provided with an opening, a rotatable part within the tube and having a channel extending from its lower end upwardly for a desired distance, said channel being intersected by a transverse opening, and said rotatable part extending above the pipe, an index-arm connected to said upwardly-extending end of the rotatable part, a graduated segment over which the index-arm works, and means for forcing or drawing the gas-producing fluid and the air into and through the pipe.

3. In a mixing and vaporizing device, the combination of a tank for containing a liquid capable of being converted into a gaseous vapor, a pipe having an opening through which air is adapted to pass and enter the interior of said pipe, a tube extending into the tank and having communication with the pipe, a check-valve for controlling said tube, another tube extending across the pipe and provided with an opening, a rotatable part within the tube and having a channel extending from its lower end upwardly for a desired distance, said channel being intersected by a transverse opening, and said rotatable part extending above the pipe, a segment above the pipe and having graduated marks upon one face, and a series of corresponding graduated indentations upon its opposite face, an index-arm connected to the upwardly-extending end of the rotatable part and working over the face of the segment carrying the graduated index-marks, and said arm having its end extending beyond the edge of the segment and beneath said segment in position to engage any of the series of graduated indentations, and means for forcing or drawing the gas-producing fluid and the air into and through the pipe.

4. In a mixing and vaporizing device, the combination of a tank for containing a liquid capable of being converted into a gaseous vapor, a pipe having an opening through which

air is adapted to pass and enter the interior of said pipe, a nipple depending from said pipe, a tube adjustably connected to the nipple and extending into the tank, a check-valve for controlling the tube, another tube extending across the pipe and in communication with the first-referred-to tube, a rotatable part within said tube and having a channel extending from its lower end upwardly for a desired distance, said channel being intersected by a transverse opening, means for turning the rotatable part so as to bring its intersecting opening into or out of registration with the opening of the surrounding tube, and means for drawing or forcing the gas-producing fluid and the air into and through the pipe.

5. In a mixing and vaporizing device, the combination of a tank for containing a liquid capable of being converted into a gaseous vapor, a pipe having its outer end open for the passage of air from the outside into the interior of said pipe, a tube extending into the tank and having communication with the pipe, a check-valve for controlling the tube, another tube extending across the pipe and in communication with the first-referred-to tube, and provided with an opening, a rotatable part within the tube and having a channel extending from its lower end upwardly for a desired distance, said channel being intersected by a transverse opening, means for turning the rotatable part so as to bring its intersecting opening into or out of registration with the opening of the surrounding tube, a partition arranged in the open end of the pipe, and having its rear edge in line with the opening of the intersecting tube, and means for drawing or forcing the gas-producing fluid and the air into and through the pipe.

6. In a mixing and vaporizing device, the combination of a tank containing a liquid capable of being converted into gaseous vapor, a pipe having an opening through which the air is adapted to pass and enter the interior of said pipe, a tube extending into the tank and having communication with the pipe, a check-valve for controlling the tube, another tube extending across the pipe and in communication with the first-referred-to tube, and provided with an opening, a rotatable part within the tube, and having a channel extending from its lower end upwardly for a desired distance, said channel being intersected by a transverse opening, means for turning the rotatable part so as to bring its intersecting opening into or out of registration with the opening of the surrounding tube, and means for drawing or forcing the gas-producing fluid and the air into and through the pipe.

In testimony whereof I affix my signature in presence of two witnesses.

JAMES E. BEAN.
